(57) **CLAIM**

We claim the ornamental design for the washer, as shown and described.

DESCRIPTION

FIG. 1 is a front perspective view of the washer embodying our design;

FIG. 2 is a cross-sectional view along line 2—2 in FIG. 3; FIG. 3 is a top plan view of the washer as shown, the opposite side being a mirror image thereof, in FIG. 1; and, FIG. 4 is a side elevational view of the washer as shown in FIG. 1.

1 Claim, 2 Drawing Sheets

FIG. 1

FIG. 2

FIG. 3**FIG. 4**
